H. G. HANCOCK.
BOW REST.
APPLICATION FILED APR. 3, 1916.

1,223,275.

Patented Apr. 17, 1917.

UNITED STATES PATENT OFFICE.

HORACE G. HANCOCK, OF NEW BRITAIN, CONNECTICUT, ASSIGNOR TO THE NORTH & JUDD MANUFACTURING COMPANY, OF NEW BRITAIN, CONNECTICUT, A CORPORATION OF CONNECTICUT.

BOW-REST.

1,223,275.

Specification of Letters Patent. Patented Apr. 17, 1917.

Application filed April 3, 1916. Serial No. 88,476.

To all whom it may concern:

Be it known that I, HORACE G. HANCOCK, a citizen of the United States, residing at New Britain, in the county of Hartford and State of Connecticut, have invented certain new and useful Improvements in Bow-Rests, of which the following is a specification.

This invention relates to what I shall for convenience term a bow-rest. As may be inferred the article is capable of general use, but it is of particular utility when employed as an automobile or other vehicle accessory, being designed in this case to sustain the bow when the top of which said bow forms a part, is folded.

The object of the invention is to provide a rest which is simple in construction, susceptible of inexpensive and easy manufacture and by which a bow or equivalent can be held in rigid relation with the rest without the use of a strap or equivalent flexible element. These rests as will be understood are generally arranged in pairs at opposite sides of a portion of an automobile or other vehicle. As I have already observed, however, they can be used in other situations and their number and disposition is not a consequential matter.

In the drawings accompanying and forming part of the present specification I have shown in detail one of several forms of embodiment of my invention. This will be set forth fully in the following description. I do not limit myself to this disclosure; I may depart therefrom in several respects within the scope of the invention defined by the claims following said description.

Referring to said drawings:

Figure 1 is a rear elevation of a bow-rest involving the invention, showing the same connected with the overhanging portion of a bracket or arm and the bow in the rest being in section.

Fig. 2 is an inside face view, and

Fig. 3 an outside face view of the parts shown in Fig. 1, the bracket being in cross section.

Fig. 4 is a top plan view of the same.

Fig. 5 is a sectional detail of the outer upper portion of the rest.

Like characters refer to like parts throughout the several views.

The device includes in its construction a suitable shank or body such as 2 and a chan-

neled rest member as 3. It is the custom as I have already noted to provide two of these bow-rests, and they are generally carried upon the overhanging portions of brackets as 4 constituting a rigid part of the automobile. As represented the shank or body 2 is perforated as at 5 to receive the overhanging portion of a bracket, the shank and therefore, the rest member 3 being maintained rigidly in some suitable manner as by the set screw 6 tapped through the base of the shank or body and adapted to engage the bracket 4. The bow 7 when the top of which the same forms a part is folded or down, is adapted to be received within the channeled rest member 3. These bow rests are comparatively common; as a matter of fact all pleasure automobiles are provided with them. In most cases, however, straps are provided to hold the bows in the channeled members 3. By my construction the use of straps which is a considerable item of expense is eliminated. As a matter of fact I can hold a bow in the rest member 3 or its equivalent in a more rigid and substantial manner than can be accomplished with straps or like means.

It will be noted that one branch of the channeled rest member 3 extends upward or outward beyond the other. The outer branch is represented as so extended, the extended portion being denoted by 8. Inside the channeled rest member 3 is a clamping or holding member as 9 associated with the extended portion 8, the latter being shown as provided on its inner face with a pocket or depression as 10 to receive said clamping or holding member when the same is in its retracted or bow-releasing position. The extension 8 is shown as having externally the boss 11 through which the screw 12 is threaded, this screw constituting a simple means for operating the bow-holding or clamping member 9. The screw at its forward or inner end is reduced or plain as at 13, the said reduced plain portion extending freely through an opening 14 in the body of said holding member 9 and at its extreme inner end being headed over as at 15 in a countersink.

While, therefore, the screw 12 has a swivelled connection with the clamping or holding member 9, the latter will be either advanced or retracted according to the direction in which the screw is turned, by reason

of the fact that shoulders or abutments on the screw receive between them the clamping member. One of these abutments is presented by the headed over portion 15, 5 while the inner end of the threaded body of the screw constitutes the other. In the present case means are provided for preventing the clamping member from rotating as the screw is run in or out. Such means 10 may be of any desirable character, although the tail piece 16 extending outwardly from the clamping member acts satisfactorily in this connection. This tail piece as shown fits in a keyway such as the notch or slot 15 17 in the upper edge of the extended portion 8. The fit between the outward extension or key portion 16 and the slot or notch 17 is a comparatively free one so as not to interfere with the proper inward or outward movement of the clamping member 9. 20 The active face of the clamping member is bulged or convexed so as not to mar the bow 7.

Initially or when the top is up, the clamping member 9 will be located in the seat or pocket 10 as best shown in Fig. 5. Said clamping member is also shown in its backward position by full lines in Figs. 1 and 4. When the bow is lowered, it will be placed 30 in the channeled or forked member 3 after which the screw 12 will be turned to the right, so that said screw advances the clamping member 9, the consequence being that the latter will engage the bow 7 and will 35 force the same solidly and substantially against the rest member 3. As shown the screw 12 is at an inward downward slant, the result being that when the clamping member is set, its lower portion acting 40 against the upper outer portion of the bow 7 tends to impart a downward thrust to the bow, so that the latter is bottomed in the rest member 3 and thus effectually held 45 against lateral and longitudinal movements, as shown by dotted lines in Figs. 1 and 4.

What I claim is:

1. In a device of the class described a

channeled rest member, a clamping member between the sides of the rest member, a screw threaded through one of said sides 50 and having a swiveled connection with the clamping member, the screw serving to advance and retract the clamping member and the clamping member having means associated therewith to prevent the rotation 55 thereof as it is operated by the screw.

2. In a device of the class described, a channeled rest member, a clamping member between the sides of the rest member, a screw threaded through one of said sides 60 and having a swiveled connection with the clamping member, the screw serving to advance and retract said clamping member, and the latter having an extension and the side through which said screw extends having 65 a notch to receive said extension, to thereby prevent rotation of the clamping member as the same is operated by the screw.

3. In a device of the class described a 70 channeled rest member, a clamping member between the sides of the rest member and having a non-rotative connection with said rest member, and a screw threaded through one of said sides, having a swiveled connection with the clamping member and also having shoulders between which 75 said clamping member is situated.

4. In a device of the class described, a 80 channeled rest member, a clamping member between the sides of the rest member, one of the sides having a notch in its upper edge and the clamping member having an extension to fit within said notch, a screw threaded through the notched side of the 85 rest member and having a swiveled connection with the clamping member, for advancing and retracting the latter.

In testimony whereof I affix my signature in presence of two witnesses.

HORACE G. HANCOCK.

Witnesses:

G. W. TROOP,
HEATH SUTHERLAND.
